Dec. 1400

Walter W. Standard of Buffalo, N. Y.

Assignor to

Jewett and Root, of same place.

Letter Patent, No. 35, dated April 9, 1861.

Whole No. 1400

The schedule referred to in this Letter Patent and making part of the same.

Boil, where it may occur;

Or it is known that I, Walter W. Standard, of the City of Buffalo, County of Erie and State of New York, assignor to Jewett and Root, of the same place, have invented or produced a certain new and original ornamental design for parlor stoves, which I denominate by the name of "Bridge", and I do hereby declare that the following is a full and exact description of the same, reference being had to the accompanying photographic plates, and the letters of reference marked thereon, in which -

Fig. I. represents the bottom plate.

" II. represents the top plate.

" III. represents the cover, and

" IV. represents the door and frame.

The bottom plate Fig. I, is elliptical in form and is surrounded at its edge by a band (a) of beads or drops.

The plain moulding (b), surrounds the elliptical bottom (c), of the fire chamber. Tangential to this moulding and spreading outwardly to the band (a), are the embossed corrugations (d), terminating in a scalloped edge as represented - and gradually lengthening and widening at the front side of the plate.

Des. 1400

An ornament (a), composed of carved or embossed scrolls and leaves is placed at the centre of the front side of the plate as represented.

The top plate Fig. II is also elliptical in form with an extension at the back for the smoke pipe and is ornamented by alternate tangential embossed (f) and carved scrolls (g) with an ornament of embossed scrolls and leaves at the centre of the front and a spirally wound band (h) at the back as represented.

The cover Fig. III has a central ornament (i), with embossed radiations (j) with fillets between terminating at the ends of the plate in the carved scrolls (k) and at the sides in the plain convex moulding (l) and having an ornamental scroll handle (m) at the centre over the central ornament (i).

The door frame Fig. IV, is ornamented by the embossed scrolls (n) at the top and scroll mouldings (o) at the bottom. The door opening is surrounded by the denticated moulding (p) with scalloped edges. In the centre of the door is a small plain elliptical surface with the number representing the size of the stove therein and a beaded border from which radiate the embossed corrugations (q). The door is surrounded by a border of parallel corrugations (r) and embossed scrolls (s) as represented.

I claim the ornamental design for a parlor stove herein described and represented in each of the accompanying photographic plates Fig. I. II. III. IV.
